UNITED STATES PATENT OFFICE

PETER CLARK AND GEORGE VAIL, OF NEW YORK, N. Y.

STAGE SETTING

Application filed October 13, 1930. Serial No. 488,330.

This invention relates to stage settings, and more particularly to changeable scenic effects.

Among the principal objects which the present invention has in view are: To provide a stage setting wherein the scenic effects may be rapidly and conveniently changed; to provide for any desired number of changes; to retain the scenes in compact form and in ready position for exposing to the audience; to mount the scenes in book form; to keep the scenes in proper centralized position; to secure simplicity of construction and operation; and to obtain other advantages and results as may be brought out in the following 15 description:

In the drawings:

Figure 1 is a front elevation of a stage setting in accordance with our invention;

Figure 2 is a sectional plan on the line 20 2—2 of Figure 1;

Figure 3 is a side elevation on a larger scale than Figures 1 and 2;

Figure 4 is a sectional rear view taken on the line 4—4 of Figure 2;

Figure 5 is a fragmentary sectional view of a lower portion of a page like member; and

Figure 6 is a detail plan of a portion of two of the page-like members at their connected parts.

30 In the description:

In the specific embodiment of the invention illustrated in said drawings, the reference numeral 10 indicates a stage or floor for the setting. The setting constituting the present invention is shown positioned adjacent the rear of the stage, and provides a plurality of upstanding page-like members 11 which can be viewed by an audience in front of the stage upon elevating the usual front curtain

40 or drop 12. While we have shown the invention in only one position, the same may have other positions upon the stage or elsewhere and may be utilized in any desired number to make up a complete stage setting.

45 In the preferred construction of our improved stage setting, we provide one leaf member 13 extending from a mid point for the complete scene to one edge of the scene and having a height for the entire height of the scene. This leaf member 13 referred to is

preferably made fast in the position where it is to be exhibited, and by way of illustration we have shown it braced from behind with rearwardly projecting braces 14. These braces are for supporting purposes only and are not intended to ever come into view from the front of the stage.

55 At the upstanding edge of the fixed leaf member 13 is hinged one of the plurality of page-like members 11 as by hinges 15, 15.

To the hinged end of this second page-like member is hinged another page-like member 11, and so on for as many pages as necessary to give the desired number of scenes. It will

be observed, only the one leaf member 13 is 60 rigidly mounted and the other page-like members 11 are successively hinged each to the next thereby enabling the same to be swung

into an open position, that is, into a position such that the last swung page-like member 11 65 can be arranged in the same plane with the next member to be swung as an extension thereof and forming the other half or section

70 of the scene to be exhibited similar to open pages of a book.

75 We preferably provide means for bracing the several members and confine the same to a proper juxtaposed relationship in use. This means as shown herein may have a re-

semblance to the end binding of a book, and is positioned at the hinged ends of said page-

like members 11 when the same are closed together, said binder-like member being

designated by the numeral 16 and hereafter referred to as the end piece. As shown in

80 Figure 2 this end piece is in a plane normal to the several planes of the closed page-like members 11 and has a hinged connection 17

85 with the outer page-like member.

90 The end piece 16 is movable in a plane normal to the closed position of the page-like members 11, and as here shown may be moved forwardly and rearwardly of the stage.

When the page-like members are in closed

95 position as in Figure 2, the end piece is at its most forward position. Upon swinging

100 the first page-like member 11 to open position, the same acts as a first class lever and moves said end piece rearward. Then as the next page-like member is swung open, it

in turn acts as a first class lever and moves the first page and the end piece rearward again. This rearward movement of the end piece and the open pages is repeated each time another page is opened.

It is preferable in carrying out our invention to guide the end piece 16 so that it will move in a defined path forwardly and rearwardly. As here shown, said end piece has a depending stud 18 which rides in a groove or track 19 in the stage floor 10. This groove or track 19 furthermore has one side thereof provided with notches 20 at appropriate intervals within which the said stud will lodge simultaneously with the completion of opening or closing any one page. Operating a page manually obtains sufficient leverage to remove said stud from the notch and yet the positioning of the stud in the notch will 20 avoid any tendency for the end piece to move of its own volition and thereby displace any of the pages.

In order that the page-like members 11 may have proper support and be readily operated, the same preferably have an anti-friction mounting on the under edge suitably spaced from the hinged end. By way of illustration, we have shown a caster 21 under each page-like member constituting the anti-friction mounting, said caster being swiveled in the page-like member and riding upon the stage floor 10.

We claim:

1. A stage setting as characterized, comprising a plurality of page-like members adapted to be swung to open position and thereby furnish a plurality of scenes, an end piece hinged to and bracing one of said members, and means for guiding said end piece.
2. A stage setting as characterized, comprising a plurality of page-like members adapted to be swung to open position and thereby furnish a plurality of scenes, an end piece hinged to and bracing one of said members, and means for guiding and retaining said end piece in successive positions thereof for each open position of the several members.
3. A stage setting as characterized comprising in combination a plurality of page-like members standing upright from the stage floor and hinged successively together, an end piece hinged to and bracing one of the said members, a stud on the bottom of said end piece, and a groove in the floor for the reception of said stud, the end piece riding backwardly and forwardly on said stud in the groove when the page-like members are swung to an open or closed position.
